J. HERRMANN,
CARRYING RACK FOR AUTOMOBILE CURTAINS.
APPLICATION FILED SEPT. 14, 1921.

1,420,699.

Patented June 27, 1922.

JOSEPH HERRMANN
INVENTOR
BY: *John D. Powers*,
ATTORNEY

UNITED STATES PATENT OFFICE.

JOSEPH HERRMANN, OF BUFFALO, NEW YORK.

CARRYING RACK FOR AUTOMOBILE CURTAINS.

1,420,699.

Specification of Letters Patent. Patented June 27, 1922.

Application filed September 14, 1921. Serial No. 500,558.

To all whom it may concern:

Be it known that JOSEPH HERRMANN, a citizen of the United States, residing at Buffalo, in the county of Erie and State of New York, has invented certain new and useful Improvements in Carrying Racks for Automobile Curtains, of which the following is a specification.

This invention relates to improvements in carrying racks for automobile curtains.

The objects of the invention are to provide a simply constructed and durable rack of permanent form which may be readily attached to any convenient supporting part of the top or body structure of the automobile, which may be manipulated with facility to provide for the insertion or removal of the curtains, and which will hold the curtains securely, accessibly and with advantages in point of compactness and the elimination of destructive folds and creases.

With the above objects in view the invention consists of certain novel features of structure and combination which will be set forth in detail as the description proceeds.

An embodiment of the invention is illustrated in the accompanying drawings wherein:

Figure 1 is a front elevation of a rack of preferred construction, and

Figures 2 and 3 are cross sectional views, Figure 2 showing the rack closed and Figure 3 showing it open.

The improved rack is of skeleton cylindrical form and comprises bars or slats 1 which are provided in suitable number and are arranged at suitable intervals apart and circular bands 2 by which said bars are carried and serially connected, the bands 2 being located near the ends of the rack, and maintaining the bars 1 in the corresponding circular arrangement which determines the cylindrical form of the rack.

The bands 2 are of split construction and their terminals are formed for connecting engagement with one another. In the construction preferred one terminal of each band 2 is provided with hooks 3 and the other terminal is provided with an eye 4 through which the hooks 3 may be engaged.

The bands 2 are sufficiently stiff to maintain their circular or generally circular outline permanently but are sufficiently resili- 55 ent to enable their ends to be sprung apart when the fastening devices 3 and 4 have been disengaged. In the construction

preferred the bands 2 are formed of twisted wire of suitable gauge, wire of such form having the necessary qualities of stiffness and resiliency. The bands 2 may be connected to the bars 1 in any suitable manner but where said bands are formed of twisted wire the connections between them and the bars 1 preferably comprise loops 5 alternating with the twisted portions of the bands. 60 The loops 5 encircle the bars 1 and also securely engage them with strong frictional pressure, being preferably embedded to a slight extent in the material of the bars. 65

The stiffness of the bands 2 is such that 70 the rack may be supported, that is to say suspended in a horizontal position, by means of one of its bars 1, selected as the circumstances of use may require and attached by screws to any suitable part of the framing or body. As attached to the supporting part, e. g. one of the bows or side bars of the top frame, the portion of the rack which may be opened up is presented at the front of the rack where the fastening parts 80 3 and 4 are readily accessible and the curtain may be inserted or removed with facility. If a bar near the upper side of the rack, for example the bar from which the fastening parts 3 or 4, as the case may be, 85 project, be used for the purpose of attachment it may be desirable to augment the stiffness of the adjacent portions of the bands and for this purpose an extra strand of wire 6 may be incorporated with each 90 band and arranged to lie adjacent the outer sides of the loops 5 with its ends coiled about or suitably articulated with the adjacent twisted portions of the band.

The curtain or curtains to be carried in 95 the rack are first rolled compactly into cylindrical form after which, the fastenings 3 and 4 being disengaged, the bars 1 adjacent said fastenings are sprung away from one another to an extent sufficient to permit the rolled curtains to be inserted between them into the cylindrical confining frame which the rack provides. The said bars 1 are then allowed to spring back or are brought back to their original relations and the fastenings 3 and 4 engaged. 100 The roll of curtains thus inserted in the rack will be engaged frictionally and securely held in place by all of the bars 1, such frictional engagement being aided by 105 the expanding tendency of the roll.

The rack takes up little space in the car,

2
requires no supporting means other than one of its frame bars, is always accessible for the insertion or removal of the curtains, permits of such insertion or removal in a few moments and with little effort and holds the curtains in the form of a roll with resultant advantages in compactness and the elimination of destructive creases. Moreover the rack, while resilient, has the advantage of permanence of form and as attached to a supporting part of the frame or body will be immovable, regardless of the swaying or vibration of the car.

Having fully described my invention, I claim:

1. As a new article of manufacture a curtain carrying rack of skeleton permanently cylindrical form comprising a series of spaced parallel longitudinal bars and split circular bands serially connecting the bars, said bands being of substantially annular form with their ends normally unsecured and being composed of relatively stiff but

resilient material, each band being provided with co-operating terminal fastening parts 25 and one of said bars serving for the attachment of the rack to a supporting part.

2. As a new article of manufacture a curtain carrying rack of skeleton permanently cylindrical form comprising a series of 30 spaced parallel longitudinal bars and split circular bands serially connecting the bars, said bands being of substantially annular form with their ends normally unsecured and being composed of twisted wire, where- 35 by said bands are relatively stiff but resilient, said bands having loops alternating with the twisted portions of the wire, the loops encircling and frictionally engaging the bars, each band being provided with 40 co-operating terminal fastening parts and one of the bars serving for the attachment of the rack to a supporting part.

In testimony whereof I affix my signature.

JOSEPH HERRMANN.
